CLAIM

I claim the ornamental design for an artificial composite neural tissue construct device, as shown and described.

DESCRIPTION

FIG. 1 is a perspective view of an artificial composite neural tissue construct device showing my new design;

FIG. 2 is a side view thereof;

FIG. 3 is a side view thereof;

FIG. 4 is a front view thereof, the back view being the same;

FIG. 5 is a perspective view thereof, including a magnified inset of the layered fibers;

FIG. 6 is a further magnified view of the layered fibers; and,

FIG. 7 is a perspective view thereof; including a magnified inset of the extension fibers.

The broken line showing at the end of the extension fibers is included for the purpose of illustration portions that do not form part of the claimed design.
